UNITED STATES PATENT OFFICE

119,521

DESIGN FOR A JAR

Jack L. Hendrickson, Wheeling, W. Va., assignor
to Colgate-Palmolive-Peet Company, Jersey
City, N. J., a corporation of Delaware

Application December 13, 1939, Serial No. 88,876

Term of patent 14 years

To all whom it may concern:

Be it known that I, Jack L. Hendrickson, a citizen of the United States, residing at Wheeling, in the county of Ohio and State of West Virginia, have invented a new, original, and ornamental Design for a Jar, of which the following is a specification, reference being had to the accompanying drawing, forming part thereof.

Figure 1 is a front perspective view of the jar showing my new design.

Figure 2 is a side elevational view thereof.

Figure 3 is a plan view.

I claim:

The ornamental design for a jar, as shown.

JACK L. HENDRICKSON.
